UNITED STATES PATENT OFFICE

2,484,964

LATCH

Otto C. Sare, Indianapolis, Ind.

Application January 4, 1946, Serial No. 638,940

1 Claim. (Cl. 292—237)

1

This invention relates to door latches and holders for swinging doors of the variety commonly used more particularly on garages, barns, warehouses or other similar structures. The principal purpose of the invention is to provide a device of this class which is positive in operation and at the same time simple in construction and inexpensive to manufacture.

Another object is to so arrange the several parts of my device as to enable it to serve as a supporting holder for a door when the same is closed and to serve likewise when the door is opened.

The accompanying drawings are illustrative of a practical but non-limiting exemplification of the invention, wherein:

Figure 1 is a front elevation of a form of the device attached to the upper front corner of the inside of a door, said door being in locked position.

Figure 2 is a partial cross-section and side elevation of the same.

Figure 3 shows the device in use on the outside of a door, its position in this instance being near the bottom front edge of the said door.

Figure 4 is a fragmentary perspective view illustrating the latch member and a portion of its operating means.

Referring particularly to Figures 1 and 2, a section of the door is indicated at 1. When the device is used on a pair of double doors to latch them in closed position from the inside, it will be attached to the door which carries the molding strip or astragal which fits over the front edge of the other door, and thus prevents opening of the latter. The upper span of the door frame or header is shown at 2 and has secured thereto the usual door-stop molding 3. Bolted to the header, as shown for example, through the stop molding, is a substantially U-shaped keeper 4. Bolted to the inside of the door is a bracket shown at 5 which is bent inwardly at right angle at its lower end, as at 6. A circular aperture is formed in the inturned part 6. The upper part of the bracket 5 is also bent inwardly to form an arm 7 which extends horizontally for a distance and is then bent slightly upward, and, from the last-named point of deflection, has a longitudinal slot running centrally through it to its extremity, thus forming a pair of parallel arms, or bifurcations, 8 which terminate in slightly enlarged, rounded outer end portions 9. Horizontally aligned openings 10 in the rounded portions are designed to receive a hinge pin 11 on which a latch member 12 is pivotally mounted.

2

Secured to the door at a point below the lower end of the bracket 5 and in vertical alignment therewith is a second bracket 13, which is of the simple L-type and has in its horizontal leg a circular aperture similar to the one in the in-turned part 6 of the bracket 5 and in direct vertical alignment therewith. A rod 14 is inserted through the apertures in the members 6 and 13 and has formed at its lower extremity a knob or ball by which the rod may be grasped for operation. The upper extremity of the rod projecting above the portion 6 is threaded to receive a bifurcated yoke 15, the arms of which extend upwardly and straddle the upper arm 7 of the bracket 5 and are pivotally attached at their upper extremities to the latch member 12.

The brackets 5 and 13 are attached to the door in such position that when the said door is closed the arm 7 will extend through the keeper 4 and rest firmly thereon, thereby acting as a support for the door to prevent it from sagging, as well as releasably holding it in its closed position. As readily seen in Figure 2, the latch member 12 is reduced in width midway of its length, thus forming an end-shouldered, bottom-inclined plate portion or tongue 16. In closing the door, the inclined under side of the tongue will contact the near side of the keeper 4, and thereby rocking upon the hinge pin 11, the latch member will be lifted until the free end of the tongue has cleared the far side of the said keeper. The latch will then drop by gravity with the end shoulder of the tongue in engagement with the keeper, thus locking the door by preventing the withdrawal of the latch from the keeper.

To unlatch the door, upward pressure is applied to the knob or ball at the lower extremity of the rod 14 which forces the said rod upward and lifts the latch member 12 until the end shoulder of the tongue is once more above the keeper, whereupon the door is free to be swung open. It will be seen that the threaded end of rod 14 contacts the under side of arm 7 when the latch is actuated thus limiting pivotal movement of the latch. The threaded rod end may be advanced or retracted relative to the yoke member 15 for adjusting such pivotal movement.

In Figure 3 I have shown my device in use to secure the bottom of a door. When so used, the arrangement of the brackets 5 and 13 is reversed and the arm 7 is bent oppositely to that shown in Figure 2. The keeper 4 is attached to the floor sill 18 or directly to the floor proper close to the door opening instead of to the header, and the position of the latch 12 will be above rather than

through the keeper 4. A pin 17 is set in the rod 14 and will contact the part 6 of the bracket 5 to limit the upward movement of the said rod when it is lifted to release the latch from contact with the keeper.

It is here noted that, in the use of the device as illustrated in Figure 3, it has the effect of supporting the door against sagging in its closed position substantially the same as in its use as illustrated in Figure 2.

It is further noted that the device of the present invention is usable to hold a door in its opened position, in which use the device is to be applied to the outer face of the door and the keeper element 4 secured on an outside positioned post or other suitable support against or closely adjacent to which the door is moved in its opened position. In this particular modification in the use of the invention, the holding device will be located at a relatively high elevation or adjacent the lower edge of the door, or even at some intermediate elevation on the door.

It is still further noted that, in the application of the device to the upper portion of the door, as exemplified in Figure 2, in some cases the lower leg 6 of the bracket 5 and the still lower associated bracket member 13 may be eliminated, inasmuch as the rod 14 will hang pendent from the pivotal attachment thereof to the latch member 12. However, in the lower application of the device to the door, as shown in Figure 3, at least one of the elements 6 or 13 may be eliminated, but the other should remain to afford a support to maintain the rod 14 in an erect position and slideable through the support. So, too, in some cases, the pivotal connector element 15 may be a plain single link member instead of a bifurcated yoke as shown. Moreover, the entire construction and arrangement of the device may be varied in other particulars within the purview of the invention as defined in the appended claim.

Having now described my invention, what I claim is:

In a latching device adapted to engage a U-shaped keeper dependently supported from the top of a door and spaced from a door, a supporting bracket adapted to be arranged in abutting relation with said door and fixedly secured to the

latter, a horizontally disposed arm positioned adjacent the upper end of said bracket and having one end fixedly secured to the latter, said arm normally extending through said keeper and having a longitudinal slot extending inwardly from the free end thereof, a latch member positioned in aligned relation with respect to the longitudinal slot in said arm and having one end mounted on the other end of said arm for swinging movement about a horizontal axis, said latch member having a detent dependently supported intermediate its ends, said detent normally extending through said slot and being adapted to engage the bight portion of the U-shaped keeper, and hand actuatable means carried by the other end of said latch member for rotating the latter whereby said detent is brought out of engaging relation with the keeper, said last named means comprising a vertically disposed rod arranged in parallel spaced relation with respect to said bracket and mounted for slideable movement in the latter, a U-shaped yoke positioned adjacent the upper end of said rod and having its bight portion fixedly secured to the latter, the legs of said yoke extending upward and surrounding said arm and said latching member, and means extending through the ends of said legs and the other end of said latching member for pivotally connecting said other end of said latch member to said yoke.

OTTO C. SARE.
